FLUSH CYLINDER TUBULAR NIGHT LATCH

Andrew Erkkila, Fitchburg, Mass., assignor to
Independent Lock Company, Fitchburg, Mass.,
a corporation of Massachusetts

Application April 24, 1947, Serial No. 743,564.

7 Claims. (Cl. 70—151)

1

This invention relates to tubular latches and more particularly to latches and actuating means therefore, and still more particularly, to escutcheon construction for coupling key operated actuating means with tubular lock mechanism to manipulate the bolt thereof.

It is an object of my invention to provide for closures, doors or the like, locks including tubular casings which may readily be mounted in position by simple boring operations including such tubular latches which are spindle operable, to retract a latch bolt or a dead bolt from the inside of the door, and is key operable from the outside of the closure or door through the medium of a key cylinder which may be positioned flush with the door frame facing.

It is further contemplated by my invention to provide a lock of the type where the key operated cylinder and lock casing are fitted in borings transversely and edgewise of the door frame in offset position, employing key operation of the cylinder from the exterior to operate the bolt mechanism for retracting a spring projected latching bolt or projecting and retracting a dead bolt operating mechanism through a spindle coupled to a turn knob on the interior of the door.

Specifically, it is contemplated by my invention to provide a coupling between the key plug assembly of a cylinder lock and the spindle of a lock which is positive in operation and is easy to adjust and maintain or set in servicing.

Known to me is the provision of door locks employing mortice lock casings or tubular lock casings in which the key operated lock cylinder assembly and lock casing are mounted on the door frame in staggered intersecting position, to be applicable to thin doors while positioning the cylinder face and escutcheon therefor, substantially flush with the outside of the door. In such mechanism, actuation of the bolt may be effected by an inside turn knob directed into the lock casing. Coupling of the movement of the cylinder to the bolt spindle may be effected directly in the casing or through a connecting channel in the door frame or lock casing. The latter assembly does not require morticing of the door as does the former to join the passages between the casing and the cylinder. However, to transmit movement of the cylinder to the lock bolt operating spindle coupling may be through an escutcheon.

Gearing and tripping fingers have been employed for this purpose and located in the door frame, the lock casing or in the escutcheon.

The setting of such mechanism ordinarily re-

quires unusual attention and skill by the installer, to provide for proper throw and retraction of the bolt and to indicate in a measure the position of the bolt by the position of the cross head of the knob.

Accordingly, it is an object of my invention to provide flush cylinder key operating mechanism for locks in which the coupling between the cylinder plug bar and the spindle for the latch bolt for transmitting movement of the cylinder plug to the spindle may be effected with certainty of positioning for mounting of the lock mechanism, and thereby minimize the installer's labor. Still more particularly, it is an object of my invention to provide a coupling between a cylinder and lock mechanism which is positive in operation for setting the lock mechanism and is installed without special morticing of the door frame.

Still more particularly, it is an object of my invention to provide a coupling between the cylinder and bolt actuating spindle in which independent movement of the bolt and bolt operating mechanism does not disalign the coupling between the cylinder and the spindle for actuating the bolt mechanism.

Still more particularly, it is an object of my invention to provide a coupling mechanism, in a lock of the character described, between the key operated cylinder plug and the spindle for the lock whereby spring projected, as well as hold back and dead bolting bolts may be employed, without disaligning the coupled mechanism.

Still more particularly, it is an object of my invention to provide tubular lock mechanism for latch bolts which are spring projected and which may be dead bolted by the inclusion of auxiliary latch bolts and includes features whereby the spring projected latch bolt may be set in the hold back position, and including coupling means between the key operated cylinder plug and the spindle of the lock mechanism which minimizes chance disalignment of the mechanism parts in installation or in operation.

To attain these objects and such further objects as may appear herein, or be hereinafter pointed out, I make reference to the accompanying drawing, forming a part hereof, in which—

Figure 1 is a sectional view through a door frame including a lock in accordance with my invention;

Figures 2, 3, and 4 are elevational views through the escutcheon plate, with the mechanism in different positions;

Figures 5 and 6 are perspective views of the

key cylinder, showing the plug bar connecting mechanism;

Figure 7 is a fragmentary sectional view taken on the line 1—1 of Figure 5;

Figure 8 is a top elevation of the lock casing;

Figure 9 is an elevational view taken on the line 9—9 of Figure 8;

Figure 10 is a section taken on the line 10—10 of Figure 8;

Figure 11 is a section taken on the line 11—11 of Figure 8;

Figure 12 is a longitudinal sectional view corresponding to Figure 10, with the latch bolt in the dead-locked position;

Figure 13 is a section showing the latch and retractor in the hold-back position;

Figure 14 is a similar view, showing the latch bolt retractor mechanism in the spring projectable position;

Figure 15 is a side elevation of a dead bolt tubular lock;

Figure 16 is a similar view, with one casing section removed to show the internal mechanism;

Figure 17 is a view similar to Figure 16, with the bolt retractor mechanism turned to retract the bolt;

Figure 18 is a section taken on the line 18—18 of Figure 15.

Making reference to the drawing, my invention is illustrated in connection with a door frame 10 which is provided with a boring 11, running edge-wise from the end of the door for receiving the lock casing 12, and a transverse boring 13 for receiving a key operated cylinder assembly 14. The cylinder assembly 14 has its outer flange 15 centered and seated in the escutcheon 16 on the front or outside face of the door frame. The key plug 17 has its rearwardly projecting extension 18 projecting into the cup-shaped collar 19 and keyed thereto by the cross pin 20, for rotation therewith, the collar being provided with an outwardly turned flange 21, having shoulders 22 and 23 arcuately spaced around the cup-shaped collar 19. A stop pin 24 is provided on the cylinder assembly 14 to limit the angle of rotation of the plug.

The collar 19 is provided with an end flange 25, encasing the plug head 26 for rotation within the collar. The plug head 26 is formed with a neck 27, from which extends the turnbar 28, preferably made of square metal stock. A cross pin 29 on the neck 27 may be engaged by the shoulders 30 and 31, to drive the turn bar 28, upon rotation of the collar 19, when key operated by the key plug 17.

It will be observed that within the limits of an arc corresponding to the spacing between the shoulders 30 and 31, the turn bar 28 is independently revoluble so that no transmission occurs between the cylinder plug 17 and the turn bar 28 unless the pin 29 is in engagement with either shoulder 30 or 31, and conversely, when the key plug 17 is immovable, the turn bar 28 is free to revolve in an arc defined by the spacing between the shoulders 30 and 31, and an arc defined by the spacing between the shoulders 22 and 23, for purposes which will appear more clearly as this description proceeds.

The turn bar 28 is arranged to extend through the hub 32, trunnioned in the plate 33. Screws 34 are directed through borings in the plate 33, to engage the threaded borings 35 in the usual lugs 36, mounted on the cylinder assembly 14, thereby drawing the cylinder firmly in position seated in the escutcheon 16 with regard to the front face of the door frame 10.

The hub 32 has a square keyway 37, to receive the turn bar 28 in keyed engagement. The hub 32 is provided with an extension finger 38, to the end of which there is pivotally attached the link 39 by the cross pin 40, the cross pin 40 being headed or expanded to hold the link pivoted to the extension finger 38 pivotally mounted thereon.

It will be understood that the extension finger 38 may clear the head of the screws 34 by recessing or countersinking the screw heads in the plate 33, in a manner well understood, in order to offer no obstruction in the path of rotation of the hub and its extension finger 38.

The plate 33 is also provided with a spindle hub 41, having an extension 42 overlapped by the end 43 of the link 39, a cross pin 44 being headed to pivotally unite the extension 42 and the link 39. The hub 41 is formed with a square keyway 45 to receive, in keyed engagement, the turn knob spindle 46.

I prefer to pre-assemble the turn knob spindle 46 with the turn knob 47 (which is oval shaped) and the escutcheon 48. Accordingly, the turn knob spindle 46 is provided with a neck 49, entering the shank 50 of the turn knob 47, the shank being trunnioned in the escutcheon 48, sleeved over the extension 42 and united thereto by a cross pin 51. A split ring 52 is encircled about the shank 50, in a groove adjacent the cross pin 51, to hold the turn knob shank revolubly anchored in the escutcheon 48. The escutcheon may be affixed in position by the fastening means comprising the screws 53. The turn knob spindle is thereby coupled with the hub 32, actuated by the turn bar 28 which, in turn, has rotary movement imparted to it, within limits, by the cylinder plug 17 and the collar assembly 19 for the bar 28.

From an inspection of Figures 2, 3 and 4, it will be observed that with the turn knob spindle 46 keyed into the hub 41, clockwise rotation of the hub 41 will draw the hub 32 with it by reason of the coupling provided by the link 39. The limiting position for clockwise rotation of the turn knob 47 is effected by engagement of the link 39 with the shank 50 engaging the spindle 46. Likewise, should the turn knob be revolved counter-clockwise, as shown in Figure 4, the engagement of the back of the link 39 with the shank 50 engaging the spindle 46 will limit the counter-clockwise rotation of the turn knob 47.

The radial displacement of the extensions 38 and 42, respectively, is adequate to limit the turn knob to movement of the coupled hubs to retractor operation of a latch bolt and dead bolt hereinafter to be described, by counter-clockwise or clockwise rotation thereof. The curvature of the link with respect to the spindle 46 passing through the keyway 45 is adequate to limit the movement clockwise or counter-clockwise when the link abuts the shank 50, thereby precluding a passed-dead-center position of the cross pin 44 with regard to the cross pin 40.

The relationship of the escutcheon assembly and the coupling of the hubs 32 and 41 will appear hereinafter.

The tubular lock casing 12 includes an end plate 54 to which the rear casing segment 55 is attached by a liner plate 56, having upstruck guide fingers 57 adjacent the bolt aperture 58. The end plate metal is spun to define the screw attaching apertures 59, as well as to rivet the liner plate thereto. The semi-cylindrical casing segment is thereupon screwed or otherwise attached by fastening means 60 internesting the neck of the casing and guide fingers 57.

I provide an auxiliary latch 61, which is guided at one end in the bolt aperture 58 by shaping the casing 55 to conform thereto. The opposite end includes a shank comprising the upper branch 62 and the lower branch 63, spanning a guide rod 64, whose end 65 is affixed in the crotch of the bifurcation formed by the branches 62 and 63. The opposite end 66 is slidably guided in the crossbar 67 whose ends are anchored in the casing segments 55 and 55a to offer the abutment for the expansion spring 68, which is coiled about the guide rod 64, normally to project the auxiliary latch 61 outwardly. A camming pin 69 extends transversely of the branch 62, for purposes which will appear hereinafter.

A latch bolt 70 overlies the auxiliary latch 61, to project through the bolt aperture 58. The latch bolt is carried by a shank 71, having bifurcated branches 72 and 73, each formed with sliders 74 and 75 extending into guide slots 76 and 77, respectively, in the casing segments.

The shank branches 72 and 73 are joined by a cross web 78 which may span the crossbar 67 carrying a guide bar 79 for the coiled spring 80, to engage the shoulder 81 of the latch bolt nose 70, thereby spring projecting the latch bolt 70 through the bolt opening 58.

Rearwardly, the branches 72 and 73 of the shank 71 are provided with guide edges 82 and 83, spanning the neck of the hub 84 which is revolvably mounted in the bearing 85, struck up from the body of the casing segment 55.

The hub 84 carries a retractor 86. The retractor 86 has a shoulder 87 to engage the stud pin element 88 on the branch 72 of the latch bolt shank for clockwise rotation of the hub 84. The retractor has a camming cutout 89 of general V-shaped contour adjacent the periphery thereof, and within which may fit the finger 90 of the pawl 91, which is pivotally carried on the pin 92, which is directed through the branch 72 of the latch bolt shank, and terminates into a bearing 92a. A slot 92b, formed in the branch 72, guides and permits the bolt shank to slide back and forth within the limits of extension of the slot.

The pawl 91 has a dogging nose 93 formed to engage a stud 94 on the latch bolt shank. A guiding edge 95 may engage the pin 69, to guide the dogging nose 93 out of the path of engagement with the stud 94, when the auxiliary latch 61 is in the projected position. A spring 96 has a loop 97 mounting the same on the pin 92. The ends 98 and 99 bear on the pawl 91 and hub 84, respectively, normally to urge the dogging nose 93 into abutting position with the stud 94.

The pawl 91 is formed with an angularly directed camming edge 100, arranged to be engaged by the pin 69 for tripping the pawl from the stud engaging position shown in Figure 12, when the auxiliary latch 61 is depressed to a position projecting the nose 93 clear of the path of the stud 94, shown in Figure 10.

The retractor 86 is formed with a curvilinear camming face 101, arranged to engage the retractor pin element 102 for retraction of the latch bolt upon counter-clockwise rotation. The camming face 101 merges into a peripheral bearing surface 103 which is curved outwardly at 104 to form a stop seat, as will appear hereinafter.

The tubular casing is completed by the semi-circular complementary section 55a. A cap 105, formed with a bayonet slot 106 serves to hold the two halves of the casing 55 and 55a at the cylindrical portion 107 by a partial rotary move-

ment, to have the pin 107a enter the anchoring branch of the bayonet slot.

The operation of the lock mechanism is as follows: Rotation of the spindle 46 clockwise will serve to rotate the hub 84, carrying with it the retractor 86, to effect engagement of the camming face 87 with the stud pin 88. The same movement initially causes the cutout 89 to move clockwise, to have the face 89a cam the branch 90 away from it, to pivot the pawl 91 in a clockwise direction and move the nose 93 out of the path of the lug 94. As rotation is continued the shank pin 88 is engaged to withdraw the latch bolt. Upon movement of the shank, shoulder 81 of the latch bolt 70 engages an offset shoulder 108 of the auxiliary latch 61, to retract both the latches 70 and 61 in unison. A finger 108a is directed against the branch 73 of the shank to keep the two shanks in parallelism.

The web 78 abuts against the crossbar 67 to restrain the latch bolt to the limited outward projection by the spring 80. The offset shoulder 108 engages the latch bolt shoulder 81 to restrain outward projection of the auxiliary latch 61. The latch bolt, auxiliary latch, crossbar and their respective springs may be assembled and inserted as a unit into the casing.

When mounted in a door or like closure, the latch bolt may be independently depressed as the latch bolt camming face 70a strikes the strike plate 70b in the door frame. The strike plate aperture is not large enough to receive both the latch bolt and the auxiliary latch in the depressed position, as shown more clearly in Figure 12, thereby depressing the pin 69 and sliding it away from the face 95, to permit the spring 96 to direct the pawl nose 93 rearwardly of the lug 94, thereby dead-bolting the latch bolt 70. Upon counter-clockwise rotation of the spindle 46, when viewed as in Figures 10 to 12, the retractor surface 89b engages the pawl 91, to tilt the pawl 93 out of the path of the lug 94, as in the previously described operation. As the retractor 86 continues in its movement, the camming surface 101 engages the retractor pin 102, to withdraw the latch bolt out of the strike aperture, the periphery of the retractor beyond the surface 89b holding the pawl out of engagement with the lug 94. Continued rotary movement of the retractor 86 brings the seat 104 into contact with the retractor pin 102, so that the limit of eccentricity of the edge 103 (see Fig. 10) of the camming surface 101 is passed the dead center with respect to the axis through the hub 84, the dead center position being intended to mean an aligned position of the three elements, to wit, the center of the pin 102, the point of contact of its periphery with the edge 103 and the center of the retractor 86. The pressure of the spring 80 holds the latch bolt in the retracted position since the bolt spring pressure exerts a turning component on the retractor in the direction in which the retractor is being turned and acts as a detent.

In a clockwise movement of the retractor to the limit of position as shown in Figure 14, it will be observed that the camming face 87 with relation to the pin 88 never reaches a passed-dead center position so that the projection by the spring 80 is possible. The lock mechanism therefore has the feature of "hold-back" of the latch bolt and auxiliary latch bolt in a counter-clockwise rotation of the spindle 46 from the interior of the door as viewed in Figures 10 to 14, with no "hold-back" features when the spindle is rotated by the knob 47 in a clockwise direction.

7

Where actuation of the lock mechanism is by the key **K** from the outside of the door, rotation of the rearwardly projecting extension **18** carries with it the collar **19** by the keying engagement effected by the cross pin **20** within the limits of the spacing between the shoulders **22** and **23** with respect to the pin **24**. The turn bar **28** will be moved, depending upon the position of the pin **29** with relation to the shoulders **30** and **31** on the collar **19**.

Upon clockwise rotation of the key, movement of the rearwardly projecting extension **18** is prevented by the shoulder **22** engaging the pin **24**. Counter-clockwise rotation of the key will cause rotation of the extension **18** within the limits of the distance between the shoulders **22** and **23**, to engage the pin **24**. The counter-clockwise movement of the key by one standing on the key side of the door thereby moves the turn bar **23** in a clockwise direction, as viewed in Figures 2 to 4, to likewise transmit clockwise rotary movement to **4**, to likewise transmit clockwise rotary movement to the hub **41**. This, in turn, will withdraw the bolt by the turning movement of the hub **84** from the position of the bolt shown in Figure 12 to the position of the bolt shown in Figure 14. During this manipulation, the coupling for the links **32** and **41** moves from the position shown in Figure 2 to the position shown in Figure 3. The limiting position under this mode of operation is where the link **39** engages the shank **59** of the spindle **46**, which projects through the hub **41**.

For knob operation in the clockwise direction, as viewed in Figure 3, retraction from the position shown in Figure 12 to the position shown in Figure 14 is accompanied by a movement of the coupling between the hubs **32** and **41** in the escutcheon from the position shown in Figure 2 to the position shown in Figure 3. The unstable position of the pin **88** with respect to the surface **87** permits of immediate spring projection when the knob **47** is no longer manually restrained.

A clockwise rotation of the knob **47** will result in a change from the position shown in Figure 12 to that shown in Figure 13, causing movement of the coupling housed within escutcheon to the position shown in Figure 4. Overturning beyond the position shown in Figure 4 is again prevented by the link **39** which is brought into engagement with the shank **59** of the spindle **46**, to cooperate with the camming surfaces **103** and **104**, to hold back the latch in the fully retracted position.

By the construction thus described, the same lock mechanism is available for use as a spring projected latch, as a dead-bolting latch, or as means to hold back the spring projected latch in the fully retracted position.

It will likewise be observed that the coupling between the hubs **32** and **41**, through the turn bar and the lost motion connection with the cylinder plug, permits operation of the inside turn knob **47** without influencing the cylinder mechanism.

While I have shown and described a tubular lock and operating mechanism therefor, employing a spring projected latch bolt including an auxiliary latch for dead-bolting the latch bolt, it will be understood that the auxiliary latch mechanism may be omitted, and the features of retraction and "hold-back" of a single spring projected latch bolt may be secured by the elimination of the retractor coupled dogging member or pawl **91**. It will also be understood, under such mode of operation, that the pawl camming means in the form of the cam surfaces **89a** and **89b** may be omitted or remain inactive. Thus, by retaining the camming face **70a** on the latch bolt, and the elimination of the auxiliary latch **61** and the pawl

or dogging mechanism **91**, the dead bolting mechanism only will be rendered inactive.

Where, however, a dead bolt is desired I may employ an assembly embodying some of the above features, as more clearly illustrated in Figures 15 to 18.

In such construction, the end plate **54** and back casing segment **55** are employed. There is provided, however, a dead bolt **70b** which is slidably extended from the bolt aperture **58** and the guiding section **51**. The bolt has a shank **109**, one end of which is headed in the bolt, the opposite end of which includes the bifurcated sections **110** and **111** which corresponds to the sections **72** and **73** previously described, which span the hub **112**. Sliders **113** and **114** are guided in slots adjacent the parting segments of the casing sections **55** and **55a**. A trunnion pin **115** pivotally supports the dogging member or pawl **116** and also passes through the guide slot **117** in the shank segment **110**. The slot **117** is extended within the limits of the throw of the bolt inwardly and outwardly, as will be apparent as this description proceeds.

The hub **112** is formed with a retractor flange **118** and has a camming slot **119** spanning the pin **120**, riveted to the bolt shank segment **110**. The hub **112** is formed peripherally with bearing portions to trunnion the hub in the bearing portions **121**, formed in the casing segments.

Axially, the hub is formed with a keyway **122**, preferably of square cross section, to receive a spindle of a turn knob, such as **46**, described in the prior embodiment. The retractor flange **118** is formed with a camming preipheral segment **123**, lying in the path of the short branch **124** of the dogging member **116**.

Normally, a spring **125** mounted on the pin **115** has one end **126** anchored on the hub **112** and the opposite end **127** adjacent the nose **128**, to pivot the nose **128** axially against a limiting pin **129** and behind the lug **130**, struck up from the latch bolt shank to dog the dead bolt.

For retraction of the bolt upon clockwise rotation of the retractor flange **118** through the turn knob spindle, the initial action of the retractor flange is to cause the camming portion **123** to engage the branch **124**, and to pivot the same in a clockwise direction, tilting the nose **128** from behind the lug **130**. Continued clockwise rotation of the retractor flange will withdraw the shank and the bolt it carries rearwardly.

I prefer to indent the casing segment **55a** with an inwardly directed protuberance **131**. Cooperating with this indented portion, I provide a leaf spring **132**, one end **133** of which is attached to the latch bolt shank. The other end **134** presses against the side wall of the casing segment **55**, to ride upon the section **135** in the retracted position of the latch bolt, or to climb up on the indented portion **131** in the projected position, the indented portion **131** and the finger **132** providing a detent for the latch bolt, to seat the latch bolt in the retracted position or in the projected position, without lost motion. Other detenting means will readily occur to the skilled worker.

As in the prior embodiment, the casing segment **55a** engages the struck up finger **136**, to hold the casing segment adjacent the forward end of the end plate. A cap **105a** engages the cylindrical end **107** of the casing segments, and closes the casing by the bayonet slot and pin **106** and **107a**, respectively, to join the casing segments.

As in the prior embodiment, the escutcheon plate **33** carrying the coupling more specifically il-

8

lustrated in Figures 2 and 4 is available for transmitting the rotary movement of a key operated cylindrical lock plug to the spindle passing through the hub 112, for operating the retractor carried thereby. The limiting movement for projection, as shown in Figures 15 and 16, or retraction, as shown in Figure 17, is accompanied by a positioning of the hubs 38 and 41 and the intermediate link 39, as more clearly described and illustrated in connection with Figures 2 to 4.

It will thus be observed that a novel tubular lock assembly has been provided, particularly suitable for exposing the cylinder lock escutcheon plate flush with the door facing, and which may be mounted upon the door simply by a transverse and edgewise boring, requiring little or no morticing operations.

The escutcheon assembly, for coupling the movement of the cylinder plug and the interior turn knob spindle, is of positive action and assures an easy installation, without special care in orienting the hubs of the cylinder lock, and the spindle 46 passing through the lock casing.

With an assembly comprising the escutcheon plate 33 and the escutcheon cover 48, disalignment of the hubs 32 and 41 is avoided, as will be clear from the limiting positions of the link 39 as appearing in Figures 3 and 4, wherein this link abuts the shank 50 of the spindle 46 in either limiting position thereof.

It will further be observed that while I prefer to combine all of the desirable features in either the auxiliary latch and coupling assembly of the escutcheon or in a dead bolt tubular lock and coupling assembly of the escutcheon, separate features of my invention have utility, and my invention is to be limited only by the appended claims.

Having thus described my invention and illustrated its use, what I claim is new and desire to secure by Letters Patent, is:

1. In a door lock having a tubular casing and including a bolt projectible therefrom and retractable therefrom to a hold back position, said casing on one side having a turn knob and a turn knob operated spindle member coupled to retractor means in the casing for retraction of the bolt and said spindle member being rotatable within limits in its coupling with the retracting means to retract the bolt to the hold back position, the combination therewith of retracting means operable from the other side of the casing comprising a turn bar member having its center line extending in a plane offset from the center line of said turn knob and located on the same side of the said casing as said turn knob, a key controlled plug for said turn bar member, coupling means between said turn bar member and plug having a lost motion connection, means for journaling said turn bar member and spindle member comprising aligned hubs keyed, respectively, to said members, linking means coupling said hubs with each other in all bolt projected, retracted and hold back positions and offset from the axes of said hubs, a portion of said linking means, upon rotary movement of said hubs, traversing said axes, said turn knob spindle extending in the path of said linking means to limit the rotary movement of the hubs with respect to each other.

2. In a door lock having a tubular casing and including a bolt projectible therethrough, said casing having on one side a turn knob and turn knob spindle member, retractor means in said casing to which said spindle member is coupled, said retractor being rotatable within limits in its

coupling to retract the bolt to the hold back position, the combination therewith of a second retractor operator means comprising a turn bar member having its center line extending in a plane offset from the center line of said turn knob spindle member and accessible from the other side of said casing, a key controlled plug for said turn bar, coupling means between said turn bar and plug having a lost motion connection, means for journaling said turn bar member and spindle member comprising hubs, an escutcheon having bearing means for said hubs, said hubs being adapted to be keyed, respectively, to said members, extension finger means on said hubs, link means connecting said extension finger means to couple the hubs with each other on said escutcheon in the bolt projected, retracted or hold back positions of the turn knob spindle member, a portion of said link means, upon rotary movement of said hubs, traversing one of said hubs and said turn knob spindle member extending in the path of said linking means to limit the rotary movement of the hubs with respect to each other.

3. In a door lock in accordance with claim 1 wherein said lost motion connection comprises a cup-shaped collar mounted on the plug and in which said turn bar is journalled, and stop means on said collar comprising shoulders radially spaced from each other, and having a pin on said turn bar for selective engagement thereof with one of said shoulders of said collar, whereby the turn knob member may be operated independently of the position of the key plug.

4. In a tubular lock, a tubular casing comprising a front section and a rear section partitioned longitudinally thereof, a bolt, a shank disposed rearwardly of said bolt including sliders, slots adjacent said segments forming guides for said sliders, a hub journalled in said casing sections, a retractor mounted on said hub, a pair of retractor pin elements carried by said shank selectively engageable by said retractor, a dogging member pivotally mounted in said casing having a dogging nose for engaging an abutment of said shank, said dogging member including a camming finger and said retractor having a plurality of camming portions whereby, upon initial rotation of said retractor, said dogging member will be disengaged from said abutment and the retractor will engage one of said retractor pin elements to retract the bolt and said retractor, including a second cam engaging the other of said retractor pin elements to hold said shank in the hold back position.

5. In a door lock in accordance with claim 4 wherein said retractor may swing rotatively in clockwise or counter-clockwise direction for retraction of the bolt, said retractor having a camming portion which, in an over-center position thereof, engages a pin element and a further portion of said retractor is provided with a retractor pin seat to hold the bolt retracted.

6. In a lock in accordance with claim 4 wherein said bolt is spring projected and said retractor may swingly rotate for retraction of the bolt in clockwise or counter-clockwise direction, the retractor camming portions being located with respect to one of said pin elements initially to cam the bolt to the retractor position and in an over-center position of the retractor to locate another portion formed with a retractor pin seat to engage the pin element and hold the bolt retracted.

7. In a lock in accordance with claim 4 where-

11

in said bolt is spring projected and has a cooperatively connected auxiliary latch bolt and pawl assembly for dogging said bolt in the projected position when the auxiliary latch is in the retracted position, and wherein said retractor may 5 rotatively swing for retraction of said bolt and auxiliary latch bolt in either a clockwise or counterclockwise direction, said pawl having a tripping portion, and said retractor camming means includes a portion engaging said tripping portion of said pawl whereby, upon swinging of said retractor, the bolt is withdrawn and the bolt tripped to the undogged position and in an over-center position of the retractor, a camming por-

10

tion on said retractor engages the pin element of said shank to hold both bolts in the retracted position.

ANDREW ERKKILA.
